(57) **CLAIM**

The ornamental design for a pan/tilt tracking mount, as shown and described.

DESCRIPTION

FIG. 1 is a back perspective view of the pan/tilt tracking mount.

FIG. 2 is a perspective view of the pan/tilt tracking mount.

FIG. 3 is a top view of the pan/tilt tracking mount.

FIG. 4 is a right elevational view of the pan/tilt tracking mount; and,

FIG. 5 is a bottom view of the pan/tilt tracking mount.

The broken lines depict portions of the pan/tilt tracking mount that form no part of the claimed design.
